HEAT INSULATED RECEPTACLE

Allen D. Whipple, Alexandria, Ind., assignor to
The Mantle Lamp Company of America, Chi-
cago, Ill., a corporation of Illinois

Application April 14, 1934, Serial No. 720,587

15 Claims. (Cl. 215—13)

The invention relates to heat-insulated receptacles of the non-vacuum type, wherein a single-walled vitreous container is enclosed within and sustained by a protective jacket.

5 In devices of this character, the container and the jacket have each been provided with a neck, and these necks have been so united that the container is pendulously supported and, therefore, affords the only substantial path of heat conductivity between the hot or cold contents of the container and the outer air.

10 The invention herein described and shown involves several improvements of such heat-insulated receptacles, among which are a novel 15 construction of the container, novel means for securing the neck of the container to the neck of the jacket, the novel construction of a drinking cup which may be used as a closure for the container, and novel means for securing said drinking cup to the receptacle.

15 The invention also includes other novel features of construction which hereinafter will be explained.

20 The figure of the drawing is a vertical sectional view of a receptacle involving the several features of the invention.

25 The vitreous container 1, preferably, is made of heat-resisting opal glass, or of crystal glass exteriorly coated with a reflecting or white enamel 30 2 which, not only obscures the unsightly environing elements of the receptacle, but imparts to the container a cleanly and attractive appearance, and additionally reflects heat rays which, if not reflected, would be radiated and lost.

35 The protective jacket 3 may be made of two or more than two parts of sheet metal, but, preferably, is made of two parts 4, 5 which are preferably united by a circumferential spun seam 6.

40 The container 1 and the jacket 3 respectively are provided with necks 7, 8 which enable said container 1 to be pendulously supported from the upper extremity of said jacket, to be out of heat-conductive contact with the body of said jacket, and to constitute the only substantial path of heat 45 conductivity between hot or cold contents of said container and the outer air.

45 The neck 7 of the container 1 exteriorly is provided with circumferential flanges or detents 9, 10 which together form a groove 11 into which a 50 part 12 of the neck 8 of the jacket 3 is spun after a yielding and preferably rubber gasket 13 has been laid in said groove. Said gasket, preferably, is a good heat insulator, and, being held under pressure by the inwardly-spun part 12 of 55 the neck 8 constitutes a bond and a hermetical

seal which, not only unites said container 1 and said jacket 3, but prevents liquids and moisture from entering the space between their walls.

Receptacles of the type herein described are frequently carried in automobiles or used by picnickers, and, consequently, must be able to sustain the shocks occasioned by rough usage. They may be large enough to contain a gallon or more of liquid or a food product. When the receptacle is filled and is subjected to a lateral shock, as for 10 instance, when it is thrown down on its side, a considerable leverage will be exerted at the point of union between the necks of constituent elements which, if the gasket 13 were too rigid and resistant, would be likely to break the frangible 15 neck of the vitreous container 1. This danger is obviated by the yielding of the gasket 13 which reduces the strain on the neck of the container.

The yielding characteristic of said gasket, furthermore, guards the frangible neck of the container 1 from shocks directly applied to the neck of the jacket 3, such shocks being largely absorbed by said gasket, and prevented from reaching the neck of the container with maximum force.

20 A packing 14 of comminuted cork or other suitable shock and heat-insulating substance, is disposed between the bodies of the container 1 and the jacket 3. This substance is sufficiently packed to avoid such rearrangement of its particles while 30

in service as would reduce its resistance and render it unable to restrain pendulous movements of said container 1 and thus assist the gasket 13 in relieving the neck 7 of strains due to those 35 pendulous movements. This packing, furthermore, while it does not operate to sustain the container 1, acts to prevent a circulation of the air within the space between that container and the jacket 3 which, if permitted, would convec-

40 tively carry heat from one of these elements to the other and soon equalize the internal and external temperatures and render the heat-insulated receptacle useless insofar as its heat-insulating function is concerned. This packing 14 must be 45 kept dry, since, if moistened, it would become a good conductor of heat and readily transfer heat from the container 1 to the jacket 3. Its dryness is assured by the fact that the compressed gasket 13 hermetically seals the entrance to the space between the container and the jacket and pre-

50 vents liquids which are used in cleaning the receptacle from reaching said packing. If desired, an adhesive may be used to permanently and ad-

55 herently unite the gasket 13 to the container and the jacket.

Retention of heat in the container 1 is enhanced by giving it a substantially globular form, to thereby minimize the area from which heat energy is dissipated, it being true that the superficial area of a hollow sphere, relatively to its capacity, is less than that of a hollow body of any other shape. Due to this fact, it is possible to slightly reduce the thickness of the insulation between the container and the jacket while maintaining the full efficiency of previous structures of other shapes in which insulation of even one-inch thickness has been employed.

The jacket 3 may also be given a substantially globular form, as shown, in order that its heat-radiating area may be reduced to a minimum. Thus, there will be interposed between the contents of the container and the outer air two walls both of which minimize heat radiation and delay the equalization of internal and external temperatures.

The closure of the retainer is a heat-insulating stopper 15 which is, preferably, made of glass or similar vitreous material. This stopper is provided with a downwardly-projecting wall 16 which is slightly spaced from the neck 7 of the container so as to provide an air-insulating cavity 11 therebetween. Said stopper is also provided with an external horizontal flange 18 that terminates in a downwardly-projecting guide flange 19 which encircles the upper portion of the neck 7 of the container 1, and also of the neck 8 of the jacket 3, and is of such diameter as to maintain the downwardly-projecting wall 16 of the stopper out of contact with the neck 7 of the container 1. Said flange 19 also prevents dirt from reaching and soiling the upper end of the receptacle, and, preferably, is ornamented so as to obscure the rubber gasket 20, as well as the contents of the receptacle, said rubber gasket being disposed between the stopper 15 and the upper edge of the receptacle.

This gasket fits and is held in the cavity formed by the wall 16 and the flanges 18 and 19 of the stopper 15.

The aforesaid stopper is hollow and serves also as a drinking cup which, because of its construction, cannot turn over, and if tilted tends to right itself. Furthermore, since the exterior element thereof which is the guide flange 19, is disposed at a considerable distance from the body of said stopper, it will remain cool and will not be too hot to be grasped by the hand of the user.

The jacket 3 is provided at its top with ears 21 to which a bail 22 is pivoted. This bail is used when the receptacle is to be carried. Pivoted to these same ears is another and resilient bail 23, preferably, carrying a ball 24 which engages a receiving cavity 25 in the top of the stopper 15 to thereby hold said stopper in position, this ball being revolvable on said bail 23 so as to provide a rolling and low-friction device which will not injure such ornamentation as said stopper may possess. The stopper is provided with guiding cavities 26 for said ball, leading to said receiving cavity 25 in which said ball 24 will be held by the spring action of said bail 23 when the stopper 15 is locked in position.

The use of the above-described means for holding the stopper in position on the receptacle, eliminates the expensive screw-threaded collars constituting parts of the protective jackets of known heat-insulated receptacles, and also dispenses with the expensive screw-threaded aluminum or other metal cup caps which, hitherto, have been employed to hold stoppers in position.

In such known devices, the stoppers are not, while the locking devices therefor are drinking cups. Thus the combination drinking cup and stopper herein described, is a structure which admits of manufacture at little cost, possesses more utility than those devices of similar nature which, heretofore, have been produced and permits the use of a construction for the finished receptacle consisting of fewer and cheaper parts.

Having thus described my invention, what I claim is:

1. A heat-insulated receptacle, including a vitreous container having an exterior groove at its upper end, a yielding gasket disposed in said groove, and a protective jacket surrounding said container and provided with an upper end portion compressed against said gasket and into said groove, thereby positively interlocking the gasket with the adjacent parts of the container and the jacket.

2. A heat-insulated receptacle, including a protective jacket, a vitreous container enclosed by said jacket, a hollow vitreous stopper for said container, said stopper having a depending wall of slightly less diameter than that of the inner upper end of said container and being provided with a downwardly-projecting guide flange which surrounds the upper end of said receptacle and is of such diameter as to hold said depending wall out of contact with said container.

3. A heat-insulated receptacle, including a protective jacket, a vitreous container enclosed by said jacket, a hollow vitreous stopper for said container, said stopper having a depending wall of slightly less diameter than that of the inner upper end of said container and being provided with a downwardly-projecting guide flange which surrounds the upper end of said receptacle, and a resilient gasket disposed between said depending wall and said downwardly-projecting flange and resting on the upper end of said receptacle, said guide flange being of such diameter as to hold said depending wall out of contact with said container.

4. A heat-insulated receptacle, including a container, a protective jacket, a closure for said container consisting of a unitary stopper and drinking cup, said closure having a depression in its top, and a bail pivoted on said jacket and provided with a ball for engaging said depression.

5. A heat-insulated receptacle, including a container, a protective jacket, a closure for said container consisting of a unitary stopper and drinking cup, said closure having a depression in its top, and a bail pivoted on said jacket and provided with an element for locking into said depression.

6. A heat-insulated receptacle, including a container, a protective jacket, a closure for said container consisting of a unitary stopper and drinking cup, ears carried by said jacket, a lifting bail pivoted on said ears, and a further bail for securing said closure in position also pivoted on said ears.

7. A stopper for a heat-insulated receptacle, comprising a cup-shaped piece of vitreous material having an exterior horizontal flange which is disposed between its upper and lower ends, and a further flange extending from said horizontal flange and constituting a heat-insulated element of said stopper.

8. A combined stopper and drinking cup for a heat-insulated receptacle including a hollow body portion, a horizontal flange extending laterally

from and between the upper and lower ends of said body portion, a terminal flange extending from and disposed at an angle to said horizontal flange, and an internal depending flange 5 that is longer than said terminal flange.

9. The process of producing a heat-insulated receptacle, which involves the assembling of a vitreous container, a yielding gasket surrounding the neck of said container, and a protective 10 jacket having a neck surrounding said gasket, and finally, forcing the neck of said jacket against said gasket to thereby unite said container and said jacket and hermetically seal the entrance to the space between said container and 15 said jacket.

10. A stopper for a heat-insulated receptacle, including a hollow body portion having external supporting means disposed between its upper and lower ends, said hollow body portion extending 20 above and far enough below said external supporting means to substantially amplify its capacity and render it available as a drinking cup.

11. A unitary stopper and drinking cup, including a hollow body portion having an external horizontal flange extending laterally from and between the upper and lower ends of said body portion, a terminal flange extending from and disposed at an angle to said horizontal flange, an internal depending flange that is longer than 25 said terminal flange, a cavity in its top for the

reception of a locking element, and guiding grooves leading to said cavity.

12. A heat-insulated receptacle including a container, a protective jacket, a closure for the mouth of said container consisting of a hollow 5 body portion that is closed at one end and open at the other end and has an external supporting flange, to thereby constitute a combination stopper and drinking cup, and means for holding said closure on said receptacle. 10

13. A heat-insulated receptacle according to claim 12 wherein the holding means is permanently attached to said receptacle.

14. A heat-insulated receptacle, including a vitreous container having exterior detents forming a groove at its upper end, a yielding gasket disposed between said detents, and a protective jacket surrounding said container and provided with an inwardly-spun upper end which bears against and holds said gasket under compression 20 in said groove. 15

15. A heat-insulated receptacle including a container, an outer protective jacket, a closure for said container, a gasket disposed between the container and said closure, means on the 25 receptacle for retaining the closure in position thereon, said closure at its lower end comprising a drinking cup extending into the neck of the container.
